UNITED STATES PATENT OFFICE.

THOMAS S. HOMANS, OF BROOKLYN, NEW YORK, ASSIGNOR TO INTERTYPE CORPORATION, OF BROOKLYN, NEW YORK, A CORPORATION OF NEW YORK.

GALLEY FOR TYPOGRAPHICAL MACHINES.

Application filed October 18, 1922. Serial No. 594,327.

To all whom it may concern:

Be it known that I, THOMAS S. HOMANS, a citizen of the United States, residing at Brooklyn, in the county of Kings and State of New York, have invented certain new and useful Improvements in Galleys for Typographical Machines, of which the following is a specification.

The present invention relates to improvements in galleys of the kind used on typographical machines, and it pertains more particularly to the so-called "outside" galleys of the kind used on typographical machines of the well known linotype class, such 10 galleys being arranged to receive the type bars which are successively ejected from the casting and trimming mechanisms of the machine and to assemble the type bars side-by-side in the same order in which they are 15 cast.

The primary object of the invention is to provide a novel and improved means for assembling the type bars in the galley, whereby the relatively thick type bars of 20 the kind now produced in typographical machines, as well as the ordinary relatively thin type bars, will be properly handled and assembled in the galley, the assembling means, in the preferred embodiment of the 25 invention, being self-adjusting, so that it will accommodate itself automatically to the variations in the thicknesses of the type bars as such variations may occur, and hence it does not require the attention of the operator for such adjustments. The assembling means, according to the preferred embodiment of the invention, also accommodates itself automatically to the assembling 30 of type bars of varying lengths, so that it does not depend upon or require any adjustment by the operator to provide for such 35 variations.

To these and other ends, the invention consists in certain improvements and combinations and arrangements of parts, all as 40 will be hereinafter more fully described, the features of novelty being pointed out particularly in the claims at the end of the specification.

In the accompanying drawing:—

Figure 1 is an end elevation of an outside galley adapted to receive type bars as they are ejected from the casting and trimming mechanisms of a typographical machine, the

galley embodying type bar assembling 55 means constructed in accordance with the present invention;

Figure 2 is a perspective view, with parts broken away, showing the construction and mode of operation of the type bar assembling means;

Figure 3 is a perspective view of an ordinary or relatively thin type bar as commonly produced on typographical machines;

Figure 4 is a perspective view of a relatively thick type bar of the kind used for headings, display type and similar purposes and which are also now produced on typographical machines;

Figure 5 represents a cross section through the type bar channel leading to the galley, illustrating diagrammatically the manner in which a relatively thick type bar similar to that shown in Figure 4 is accommodated by the assembling means; and

Figure 6 is a view similar to Figure 5 showing diagrammatically the manner in which an ordinary or relatively thin type bar like that shown in Figure 3 is accommodated by the assembling means.

Similar parts are designated by the same reference characters in the several views.

The present invention is applicable generally to typographical machines of the kinds which produce type bars or slugs which bear a line of type characters on an edge thereof. The invention is particularly applicable to typographical machines of the well known linotype class, and to the so-called "outside" galleys commonly used on machines of that class and which receive and assemble side-by-side in the order in which they are cast, type bars as the same are ejected from the casting and trimming mechanisms. The invention is shown in the accompanying drawing and will be herein-after described as applied to the so-called outside galleys of typographical machines of the linotype class, but it will be understood that the invention is not restricted to machines of that particular class, as it is applicable generally to typographical machines producing type bars of the kind above described. It will also be understood that while the preferred embodiment of the invention is herein shown, the invention is not restricted to the particular construc-

tion illustrated, as equivalent constructions are contemplated and these will be included within the scope of the claims.

In the present instance, wherein the invention is shown applied to a typographical machine of the well known linotype class, 1 designates a part of the trimming knife which may be any of the well known kinds used, and through which the type bar ejected from the mold is pushed, the blades of the knife trimming the slug to exact thickness in the well known way. The type bar may be ejected from the mold and pushed through the trimming knife by an ejector 5 blade of the kind commonly used in line casting machines. A guide plate 2 is usually provided within the trimming knife for the purpose of maintaining a frictional contact on the type bar after it has been trimmed 10 and while it is being passed into the receiving mechanism of the galley.

The galley which is designated generally as 3 is located at the front of the machine and it comprises a floor or shelf 4 on which 15 the type bars T are adapted to be assembled side-by-side and in the order in which they are cast in the machine. An abutment or support 5 is arranged to receive the type bars in front of it and has a spring 6 or 20 other suitable means to provide friction which will enable the abutment or support to be shifted toward the left (Fig. 2) as the type bars accumulate in front of it and are progressively fed toward the left in said 25 figure. The feeding of the type bars follows the reception of each type bar in the line in front of the abutment or support 5, and this feeding of the line of type bars may be effected by a pusher similar to that commonly 30 used on machines of the linotype class or by 35 any other appropriate means.

The floor or shelf 3 of the galley is supported at one end by a bracket 7 which is 40 suitably secured in fixed relation to the trimming knife and in the present instance the portion 8 of this bracket which lies between the bottom wall 9 of the trimming knife and the upper rear edge of the floor 3, forms, in effect, a continuation of the upper surface 45 of the floor 3 and it provides the bottom wall or floor of a type bar passage or channel through which the type bars pass to the galley. This floor comprises a portion 10 which is located at a relatively lower level 50 and is of a width to receive the lower edge of the ordinary or relatively thin type bars similar to the type bar T in Figure 3, and a portion 11 which extends along side of the portion 10 and is located at a relatively 55 higher level, the portion 11 being adapted to serve as a support for the lower edge of a relatively thick type bar, similar to the type bar T' illustrated in Figure 4, it being 60 understood that a channel or passage-way is provided above the lower and upper floor 65

levels 10 and 11 which is of sufficient width to permit the passage of type bars which are of the maximum thickness to be accommodated. As shown, one side wall of the type bar channel is formed by the plate 12, 70 a portion of this plate being broken away in Figure 2 to illustrate the interior construction of the type bar channel. The other wall 13 of the channel may be permanently 75 fixed in place and constitute a part of the galley supporting bracket 7.

The present invention provides means for causing the type bars ejected from the trimming knife to correctly enter the type bar channel, so that they will descend lengthwise therethrough and for causing the type bars to stand in upright position on their feet during their descent through the channel, irrespective of variations in the thickness of the type bars. Such means also accommodates itself to variations in the length of the type bars. Such means in the present instance comprises a gate or deflector 14 which has an upright or substantially vertical portion 15 and a downwardly and forwardly inclined portion 16 which is connected to the upright portion 15 by an intermediate bend 17. The gate or deflector is preferably hung as a pendant from a pivot pin 18, which latter may be supported by the upper portions or continuations of the plates 12 and 13. The downwardly and forwardly inclined lower portion 16 of the gate, being forward of the pivot 18, will tend to swing the gate rearwardly, but the rearward swing of the gate is limited by a projection 19 on the gate which is arranged to abut against the forward edge of the wall 13 when the gate reaches a predetermined point in its rearward swing. The gate occupies a position between the side walls 12 and 13 of the type bar channel, its upper or upright portion 15 being in line with or opposite to the passage in the trimming knife through which the trimmed type bars are ejected and the lower inclined portion 16 of the gate lying above or opposite to the floor of the type bar channel which comprises the lower and upper levels 10 and 11. The pivotal support 18 of the gate is located sufficiently high to be above the upper end of the longest type bar to be handled. The rear face of the upright portion 15 and the under face of the inclined portion 16 of the gate are formed along one side edge of the gate with a step 20, this step 20 extending continuously from the upper upright portion to the lower inclined portion of the gate and at the latter point it is opposite to the lower level 10 in the floor of the type bar channel. A second step 21 is formed on the upright and inclined portions of the gate along side of the step 20, the portion of this step 21 on the lower inclined portion 16 of the gate being opposite to the upper level 11 on the floor of the 130

type bar channel. Preferably, the step 21 has a bevel form or it is connected to the step 20 by a beveled surface. It will be understood that the gate 14 is free to swing in a forward and rearward direction between the plates 12 and 13 and about the pivot 18 as an axis, its rearward movement, however, being limited by the projection of stop 19.

The mode of operation of the type bar assembling structure as above described is as follows: When a type bar of ordinary thickness similar to that shown in Figure 3 is pushed forwardly through the trimming knife by the ejector on the machine, the lower end of the type bar will pass from the bottom wall 9 of the trimming knife to the downwardly and forwardly inclined lower level 10, it being pushed toward this side of the type bar entrance by the friction plate 2 within the trimming knife. The upper portion of the type bar will engage the step 20 on the upright portion 15 of the gate, thereby pressing the latter forwardly to a slight extent. As the ejector of the machine recedes, the gate will press the upper end of the type bar rearwardly, thus tipping the upper end of the type bar rearwardly. The lower end of the type bar having already entered upon the lower level 10 of the floor of the type bar, will be in position to descend endwise through this channel and in entering and passing through the channel, the upper longitudinal edge of the type bar will be engaged by the step 20 on the gate, substantially as is shown in Figure 6, so that the type bar is supported and maintained in upright position while it is descending endwise through the channel, engagement of the type bar with the step 20 being caused, and lateral tipping of the type bar being prevented by the bevel which is adjacent to or connects the step 21 on the gate to the step 20 thereon. It will be understood that the gate 14 is lifted or pushed forwardly by the type bar while passing the bend 17 of the gate and while passing through the type bar entrance, after which the gate resumes its normal position with the projection or stop 19 resting against the forward edge of the wall 13, under the influence of gravity. When a relatively thick type bar similar to the type bar T in Figure 4, is ejected from the trimming knife, such type bar engages the step 21 on the gate, while the lower end of the type bar passes from the bottom wall 9 of the trimming knife onto the downwardly and forwardly sloping level 11 of the floor of the type bar entrance. The upper portion of the type bar causes the gate to swing forwardly to a slight extent, as before, and when the ejector of the machine recedes, the rearward pressure exerted by the gate on the upper portion of the type bar will be sufficient to tip the upper end of the type bar rear-

wardly and this type bar will descend endwise through the type bar channel with the foot of the type bar resting on the upper level 11 and the top of the type bar engaged by the step 21 of the gate. The gate will be deflected to a greater extent in accommodating relatively thick type bars, as compared with its deflection under the influence of the ordinary or relatively thin type bars, the gate, however, accommodating itself automatically to the variations in the thickness of the type bars. It will be understood that in handling type bars of a thickness less than the type bar T (Fig. 5) and greater than the thickness of the type bar T (Fig. 6), such type bars of intermediate thickness will be maintained in upright position while passing through the type bar channel by the bevel or incline between or connecting the steps 20 and 21 on the gate, this bevel or incline engaging the top longitudinal edge of the slug and acting under the weight of the gate to prevent the type bar from tipping away from the wall 13.

The type bars after passing through the type bar channel descend upon the forwardly and downwardly sloping bottom or floor 3 of the galley where they are stacked in a row in front of the frictionally held abutment or support 5, it being understood that the type bars are assembled successively and in the order in which they were cast in the machine, the usual stacking means being suitable for the purpose.

By providing separate supporting means and separate guiding means for type bars of different thicknesses, the type bars are appropriately received from the trimming knife and conducted to the galley so that they are maintained in upright position and are properly stacked in the galley, the type bars of varying thicknesses being accommodated automatically so that manual adjustment or other attention from the operator is not required when a change is made in the thickness of the type bar produced by the machine. Moreover, by providing a pivoted gate or deflector substantially as hereinbefore described, type bars of varying length will be accommodated automatically so that no manual adjustment or other attention is required of the operator when a change is made in the length of the type bar produced by the machine.

In the preferred construction, as herein shown, the entrance through which the type bars pass to the galley contains, in effect, separate channels which are adapted respectively for the passage of type bars of different thicknesses, the surfaces 10 and 11 in the present instance constituting the bottom walls or floors of these channels, and the surfaces 20 and 21 on the gate or deflector constituting the top walls of these channels,

the laterally beveled or inclined surface between the surfaces 20 and 21 directing the relatively thin type bars into the channel formed by the surfaces 10 and 20 and retaining them in this channel during their passage through the galley entrance; and the gate, in any case, adjusts itself to the thickness of the type bar presented to the galley entrance, so that the type bars will be properly 10 delivered from the galley entrance into the galley proper for stacking therein side-by-side and in the same sequence in which they were cast in the machine.

I claim as my invention:—

15. 1. In a galley for line casting machines, a device for directing type bars for assembly therein having a surface to cooperate with type bars of one thickness and another surface to cooperate with type bars of another thickness.
20. 2. In a galley for line casting machines, a device for directing type bars for assembly therein having relatively stepped surfaces one of which is adapted to act upon type bars of one thickness and another of which is adapted to act upon type bars of another thickness.
25. 3. In a galley for line casting machines, type bar directing means comprising relatively stepped surfaces one of which is operative on relatively thin type bars and another of which is operative upon relatively thick type bars.
30. 4. In a galley for line casting machines, a deflector movable under the influence of passing type bars, said deflector having one surface adapted for type bars of one thickness and another surface adapted for type bars of another thickness.
35. 40. 5. In a galley for line casting machines, a deflector displaceable under the influence of type bars passing into the galley, said deflector having relatively stepped surfaces adapted to act respectively on type bars of different thicknesses and to direct them to the galley.
45. 6. In a galley for line casting machines, a pivoted deflector for directing type bars to be assembled in the galley, the deflector having one surface for type bars of one thickness and another surface for type bars of a different thickness.
50. 7. In a galley for line casting machines, a galley entrance having separate floors, one floor to direct type bars of one thickness and another floor to direct type bars of another thickness.
55. 8. In a galley for line casting machines, a galley entrance having floors in laterally-stepped relation, one of said floors being adapted to direct relatively thin type bars and another floor to direct relatively thick type bars.
60. 9. In a galley for line casting machines,

the combination of a galley entrance having 65 separate floors for type bars of different thicknesses, and a deflector having separate surfaces for type bars of different thicknesses.

10. In a galley for line casting machines, 70 the combination of a galley entrance having laterally-stepped surfaces to respectively support type bars of different thicknesses, and a deflector having laterally-stepped surfaces opposite to said floors to respectively 75 direct type bars of different thicknesses.

11. In a galley for line-casting machines, the combination of a galley entrance having surfaces at different levels to respectively support type bars of different thicknesses, 80 and a deflector movable toward and from said surfaces in the entrance and having surfaces at different levels to respectively act upon type bars of different thicknesses.

12. In a galley for line casting machines, 85 the combination of a galley entrance having different channels to respectively receive type bars of different thicknesses, and a pendent deflector having an upright portion to be engaged by the type bars prior to 90 their passage into said entrance and another portion to cooperate with the type bars while passing through said entrance, said deflector having different surfaces to respectively direct type bars of different 95 thicknesses.

13. In a galley for line casting machines, 100 a galley entrance through which type bars of different thicknesses are adapted to pass for stacking in the galley, said entrance having stepped surfaces for the engagement respectively of type bars of different thicknesses.

14. In a galley for line casting machines, 105 a gallery entrance through which type bars of different thicknesses are adapted to pass into the galley for stacking, said entrance containing separate channels for the passage respectively of type bars of different thicknesses and embodying a member operative to direct type bars into one or another of said channels according to their respective thicknesses.

15. In a galley for line casting machines, 110 a galley entrance adapted for the passage of type bars of different thicknesses, said entrance providing separate channels for the passage respectively of type bars of different thicknesses, and embodying a part operative to direct type bars of one thickness 115 into one of said channels and self adjustable under the influence of a type bar of another thickness to accommodate the entrance for the passage of such latter type bar through another of its channels.

In testimony whereof I affix my signature.

THOMAS S. HOMANS.
